UNITED STATES PATENT OFFICE.

JAN CYBULSKI, OF KENT, PENNSYLVANIA.

FORCED-DRAFT MECHANISM FOR STOVES.

1,125,819.

Specification of Letters Patent.

Patented Jan. 19, 1915.

Application filed July 15, 1914. Serial No. 851,116.

To all whom it may concern:

Be it known that I, JAN CYBULSKI, a subject of the Czar of Russia, residing at Kent, in the county of Indiana and State of Pennsylvania, have invented certain new and useful Improvements in Forced-Draft Mechanism for Stoves, of which the following is a specification.

This invention relates to certain new and useful improvements in forced draft mechanism for stoves.

The primary object of this invention is to provide a means in connection with a stove whereby the combustion therein may be accelerated and the perfect operation of the stove enhanced thereby.

A further object is to provide a driven suction device in communication between the combustion chamber of a stove and the outlet flue or chimney and adapted upon operation to create a forced draft for the fire for the purpose of rekindling the fire or making the same burn with better efficiency.

A still further object is to provide a suction fan device operable by a turn crank and connected by conduits between the combustion chamber of a stove and outlet, and whereby a draft may be forced through the grate and fire of the stove whenever desired.

With these general objects in view and others that will appear as the nature of the invention is better understood, the same consists in the novel construction, combination and arrangement of parts hereinafter more fully described and then claimed.

In the accompanying drawings forming a part of this application and wherein like numerals of reference designate like parts throughout the several views: Figure 1 is a side elevation of a stove provided with the present device and with a portion of the chimney broken away and in section. Fig. 2 is a central horizontal sectional view taken through the casing of the device. Fig. 3 is a vertical transverse sectional view taken upon line III—III of Fig. 2, and, Fig. 4 is a vertical transverse sectional view taken upon line IV—IV of Fig. 2.

Referring more in detail to the drawings, the present invention broadly consists of a suction device contained within the casing 10 and mounted by means of a bracket 11 upon a stove 12, within which a forced draft is adapted to be effected by the device. The casing 10 is provided with an inlet pipe 13 tapped into the end wall 14 of the casing,

which wall is positioned adjacent the stove while said pipe 13 enters the stove at any convenient point above the fire box grate thereof.

An outlet pipe 15 is connected between the end wall 16 of the casing and the chimney or flue 17 while a by-pass pipe 18 communicates between the outlet pipe 15 and the casing 10 through the side 19 of the latter.

A transverse bracket 20 is secured within the casing between the opposite sides thereof while an upright post 21 is likewise positioned therein and spaced from the said bracket. A shaft 22 is journaled in bearings 23 carried by the top of said post and the upper side of said bracket and has one end extending outwardly of the casing and provided with a pinion 24 mounted thereon.

A turn crank 25 is rotatably-mounted as at 26 to the end 16 of the casing and is provided with a relatively larger gear or pinion 27 in constant mesh with the aforesaid pinion 24 and whereupon the shaft 22 may be revolved together with the fan 28 carried by said shaft and within the casing. The bracket 20 is provided with an arm 29 having a counter-shaft 30 journaled therein and also at the opposite ends of the casing while the projecting end of said counter-shaft is 80 provided with a small pinion 31 exteriorly of the casing and in constant mesh with the gear 27 of the crank. A fan 32 of smaller dimensions than the fan 28 is secured to a revolute shaft 33 within the casing and 85 upon the end wall 14 thereof and is journaled in a plane above the axis of the fan 28 and directly over the inlet pipe 13. The counter-shaft 30 is provided with a pinion 34 in alinement with a pinion 35 carried by 90 the shaft 33 while an idler 36 also carried by the end 14 is in constant mesh with and positioned between the said pinions 34 and 35.

The device is operated by turning the 100 crank 25 which results in simultaneously revolving the fans 28 and 32 within the casing 10. A suction is thus created in the inlet pipe 13 and the same having an entrance from the stove at a point above the burning grate thereof, it will be seen that an upward draft is created through the burning fuel upon the grate, the air being drawn from beneath the grate and the supply thereof being regulated by the stove door 37. 110 The air drawn through the stove and into the casing 10 by the fans is exhausted

through the by-pass 18 and end outlet 15 into the flue or chimney 17, the natural draft of which latter augments the action of the fans in clearing the casing. It is to be noted that the usual outlet stove pipe may be employed as a stove or the pipes employed with the present device may be solely utilized for discharging the productions of combustion from the stove.

10 The device is serviceable at any time desired for increasing the draft in the fire pot and especially when a new fire is being kindled as well as when new fuel is being added to the fire or when the fire dies down 15 and needs reviving.

While the forms of the invention herein shown and described are what are believed to be preferable embodiments thereof, it is nevertheless to be understood that various forms, modifications and arrangements of the parts as shown may be made without departing from the spirit and scope of the invention as claimed.

What I claim as new is:—

25 1. A device of the class described comprising in combination with a stove and a flue, a casing positioned therebetween, piping between said casing and flue and the combustion chamber of the stove, a trans-
20 verse bracket and a post within said casing, a longitudinally - positioned fan journaled
30

upon said bracket and post, a relatively smaller fan journaled within said casing above the axial line of said first-named fan in the same vertical plane, operating means common to both of said fans positioned exteriorly of the casing, and a by-pass outlet pipe between one side of said casing and the piping between said casing and flue.

2. A draft device comprising in combination with a stove and a chimney, and a casing positioned therebetween, of an inlet pipe for said casing communicating with the combustion chamber of the stove, an outlet pipe for said casing communicating between one 45 end of said casing and said chimney, a by-pass outlet pipe between one side of said casing and said outlet pipe, a relatively small fan journaled within said casing in a plane above said larger fan, an operative 50 turn crank exteriorly of said casing, and operative pinion connections between said crank and both of said fans whereby simultaneous operation of said fan is effected in the exhausting operation.

In testimony whereof I affix my signature in presence of two witnesses.

JAN CYBULSKI.
